[57] ABSTRACT

A device capable of reducing the background in ion probe mass spectrometry by up to seven orders of magnitude (10^7) allows separation of sputtered neutrals and high energy sputtered or backscattered ions from low energy sputtered ions. The low energy sputtered ions are fed into a mass analyzer for determination of the mass-to-charge ratio whereas the neutrals and high energy ions which usually produce a high background intensity in the mass spectra are prevented from entering the mass analyzer. This is achieved by positioning the target off-axis with respect to the relevant analyzer axis on the entrance side of the mass analyzer, by placing a shutter with an aperture between target and entrance aperture of the mass analyzer so that sputtered neutrals passing through the shutter aperture impinge on the front panel of the mass analyzer outside the entrance aperture, by producing an electric field between shutter and front panel of the mass analyzer, and by adjusting the direction and strength of the electric field in such a way that low energy sputtered ions passing through the shutter aperture can be deflected into the entrance aperture of the mass analyzer whereas high energy ions are less deflected and thus impinge on the front panel of the mass analyzer outside the entrance aperture.

**DEVICE FOR SEPARATION OF SPUTTERED
NEUTRALS AND HIGH ENERGY IONS FROM
SPUTTERED LOW ENERGY IONS**

BACKGROUND OF THE INVENTION

This invention relates to an improvement of ion probe mass spectrometers and in particular to those with a quadrupole mass filter.

Ion probe mass spectrometers are now frequently used as a means for static (surface) or dynamic (in depth) analysis of the chemical composition of solids. The respective method currently named "secondary ion mass spectrometry" (SIMS), has the following physical background:

In a target chamber evacuated by suitable pumps to a chamber pressure of less than about 10^{-6} Torr, the target surface is bombarded by a primary ion beam produced by a suitable ion gun, the energy usually being several keV. The bombardment results in sputtering of the target. The sputtered particles are partly ionized (secondary ions) and may thus be analyzed with respect to their mass-to-charge ratio in a mass spectrometer. The prior art has mainly used the method of magnetic mass separation. A review has been given by A. J. Socha published in *Surface Science* 25 (1971) 147. More recently electrical quadrupole filters have been applied successfully for mass analysis in ion probe mass spectrometers. A description and discussion may be found in a paper by A. Benninghoven and E. Loebach published in *The Review of Scientific Instruments* 42 (1971) 49.

One problem encountered in constructing an ion probe mass spectrometer, results from the fact that the sputtered particles have an energy distribution with a broad peak at some eV ("low energy ions") and a slowly decreasing tail extending to energies of the order of the primary ion energy ("high energy ions"). The high energy ions are the main cause of trouble with respect to the ion optical lay-out of the apparatus since these ions produce tails in the mass lines and thus reduce both the mass resolution and the sensitivity in trace analysis.

Additional complications arise in cases where a quadrupole analyzer is used since this type of mass analyzer is only able to filter ions that have an energy below about 50 eV. Secondary ions and backscattered primary ions with an energy above this limit pass through the quadrupole unfiltered and may enter the ion detector, thus causing a background in the mass spectrum. Moreover sputtered neutrals entering the quadrupole may produce ternary ions by means of sputtering internal surfaces or via collision with residual gas molecules. These ternary ions also pass through the remainder of the quadrupole unanalyzed and cause a strong background in the mass spectrum.

In a very recent paper given by us (K. Wittmaack, J. Maul and F. Schulz, *International Journal of Mass Spectrometry and Ion Physics* 11 (1973) 23), we have demonstrated the necessity to prevent sputtered neutrals and high energy sputtered or backscattered ions from entering the quadrupole if one wants to achieve a peak-to-background ratio of better than 10^4 .

Accordingly the object of the invention is to add a means to mass analyzers, in particular to quadrupole filters, which allows both suppression of all unwanted

particles and passage of a high amount of analyzable secondary ions.

SUMMARY OF THE INVENTION

5 In the improvement of ion probe mass spectrometers herein presented the target is mounted off-axis with respect to the relevant analyzer axis on the entrance side of the mass analyzer. Between target and entrance aperture of the mass analyzer a shutter with an aperture is
10 arranged in such a way that the straight line defined by the center of the target and the center of shutter aperture crosses the analyzer axis in front of the entrance aperture. Dimension and position of the shutter aperture are arranged in such a way that sputtered neutrals passing through the shutter aperture impinge on the front panel of the mass analyzer outside the entrance aperture. Between entrance aperture of the analyzer and shutter aperture a deflecting electric field is produced between electrodes of any conventional design and fabrication. The direction and strength of the electric field are adjustable so that the low energy sputtered ions which pass through the shutter aperture can be deflected into the mass analyzer whereas the high energy ions are less deflected and impinge on the front panel of the mass analyzer. The potential of the shutter and the target with respect to the mass analyzer are adjustable to achieve optimum operating conditions.

20 In one embodiment of the invention, the electric field is a static one produced between two electrically conductive surfaces. In another embodiment the electric field is produced by a plate capacitor.

25 Using this kind of set-up, one is able to prevent all unwanted particles from entering the mass analyzer. The background intensity in the mass spectra may thus be reduced to the electronic noise level of the ion detection system. The gain in sensitivity in trace analysis obtained by adding this set-up to a quadrupole mass filter has been found to amount to 4 to 7 orders of magnitude depending upon the respective experimental conditions.

30 Since the present invention is of a very simple design it may be added to any target-mass analyzer arrangement. The invention provides an outstanding improvement to ion probe mass spectrometers with quadrupole analyzer, it may also be used successfully in combination with magnetic mass separators.

35 The features of our invention which are believed to be novel are set forth with particularity in the appended 50 claims. The invention will be more fully understood from the following detailed description of the arrangement and a presentation of the improvement taken in conjunction with the following drawings.

BRIEF DESCRIPTION OF THE DRAWINGS

FIG. 1 is a schematic representation of a device for separation of sputtered neutrals and high energy ions from sputtered low energy ions.

FIG. 2 is a transverse sectional view of the structure 60 of a device for separation of sputtered neutrals and high energy ions from sputtered low energy ions.

FIG. 3 shows a typical secondary ion mass spectrum obtained upon sputtering an aluminium target using a quadrupole analyzer without a means to suppress unwanted particles.

65 FIG. 4 shows the spectrum corresponding to that of FIG. 3, obtained after suppression of unwanted particles.

DETAILED DESCRIPTION OF PREFERRED EMBODIMENTS

Referring to FIG. 1, there is shown a quadrupole mass analyzer 1 with an entrance aperture 2 in a front panel 10. Sputtered particles are produced by bombardment of a sample 3 with a primary ion beam 4. The sample 3 is mounted on a target electrode 5, which is rotatable with respect to the axis normal to the drawing plane and movable parallel to the direction of primary beam incidence. Between target 3 and aperture 2 a shutter electrode 6 with aperture 7 is mounted. Shutter 6 allows only part of the sputtered or backscattered particles to enter through aperture 7 into the region between shutter 6 and front panel 10. The beam of secondary particles emitted from sample 3 and passing through aperture 7 defines an axis 8 which, by suitably positioning sample 3 and aperture 7, intersects the front panel 10 at a point 9 outside the entrance aperture 2. Consequently the sputtered neutrals 15 out of the secondary beam passing through aperture 7 impinge at point 9 on the front panel 10 and thus do not enter the mass analyzer 1 via aperture 2. The electrostatic field 11 produced between shutter 7 and front panel 10 by use of suitable electrodes (not shown in FIG. 1), is adjusted with respect to field orientation and field strength so that low energy sputtered ions 12 enter into the mass analyzer 1 via aperture 2 whereas high energy backscattered or sputtered ions 13 and very low energy ions 14 hit front panel 10 outside aperture 2. A special shape of the electrostatic field 11 is not required, yet direction and strength of the electrostatic field 11 along the path of low energy ions 12 must be such that these ions pass through aperture 2 parallel to the relevant axis of the mass analyzer. The electrostatic potential of sample 3, target electrode 5 and shutter electrode 6 may be adjusted with respect to the potential of the mass analyzer so as to achieve optimum line intensity in the mass spectra.

Referring now to FIG. 2, there is shown a sectional view of one embodiment of the inventive device. The primary ion beam 4 hits the sample 3 at an angle ν with respect to the target normal. The secondary beam 8 passes through aperture 7 in shutter electrode 6 into a space defined by a plate capacitor made up by the couple of plate electrodes 16, 17. The two surfaces 18, 19 of electrodes 16, 17 are facing one another. Applying a voltage to the plates 16, 17 an electric field is produced between surfaces 18, 19, as indicated by arrow 11. The straight line 20 which passes through the center of aperture 2 is a symmetry axis of the electrodes 16, 17. Line 20 and the straight line 8 which designates the axis of the beam of sputtered neutrals 15 intersect one another at an angle α . Aperture 2 must lie in the plane of ion deflection which is defined by line 8 and the direction of the electrostatic field 11. Shutter 6 with aperture 7 is movable on capacitor bounding plate electrode 21 which contains a large opening 22 partly masked by shutter 6. Shutter 6 is fixed to plate 21 via the guiding support 23. Plate 21 is mounted to 16, 17 via isolating eyelets 24 whereas the plate capacitor is fixed to the front panel 10 of quadrupole 1 via insulating eyelets 25.

By suitably adjusting direction and strength of the electrostatic field 11, e.g. about 3 volts/cm in case of the embodiment shown in FIG. 2, low energy secondary ions 12 are deflected into aperture 2 whereas high energy ions 13 and very low energy ions 14 hit the front

panel 10 outside aperture 2. Optimum operation conditions with respect to a high ratio of peak to background intensity in the mass spectra may be obtained by moving and rotating target electrode 5 with sample 3, by changing the angle α via moving shutter electrode 6 with aperture 7, and by fitting the dimension of aperture 7 to the dimension of the target area investigated.

Referring now to FIGS. 3 and 4, there is demonstrated the reduction in background intensity in ion probe mass spectrometry with a quadrupole analyzer by means of using a device for separation of sputtered neutrals 15 and high energy ions 13 from sputtered low energy ions 12, in particular by means of using the embodiment shown in FIG. 2. The results shown in FIGS. 3 and 4 were both obtained by bombardment of an aluminium sample with a primary ion beam 4 of 10 keV Argon ions.

FIG. 3 was obtained without a means to suppress sputtered neutrals 15 and high energy ions 13. The sample was placed on axis of the quadrupole analyzer 1. One can see that the mass spectrum is disturbed by a background of high intensity B, nearly independent of mass number. The intensity ratio of peak $^{27}\text{Al}^+$ to background, P/B is only about 10. This is too low by several orders of magnitude to allow trace analysis in the parts per million range or below.

FIG. 4 was obtained by using the embodiment shown in FIG. 2. One can see that a background is no longer observable on a linear scale. The intensity ratio of peak to background, P/B is now about 10^8 . From a comparison with the results of FIG. 3 one can see that the gain in sensitivity obtained by using the inventive device amounts to about 10^7 . The reduction in peak intensity at the same time is only about 50%, due to the low energy dispersion of the device, aimed at in constructing the embodiment of FIG. 2.

Using the inventive device one may thus carry out trace analysis down to the parts per billion range.

An additional advantage obtained by using the inventive device may be deduced from a comparison of the line shape of the $^{27}\text{Al}^+$ peak in FIGS. 3 and 4. One can see that the tail T observed in FIG. 3 has disappeared in FIG. 4. Moreover the full width at half maximum, FWHM of the $^{27}\text{Al}^+$ peak is reduced from 0.5 to 0.3 at the same setting of the quadrupole resolution. Both effects are due to a suppression of those sputtered high energy ions which have an energy at the upper limit of detectability. This additional advantage of the inventive device allows a determination of trace contaminants with mass numbers in the neighborhood of strong mass lines, e.g. those of the matrix material.

While there has been described in FIG. 2 what is presently considered the preferred embodiment of the invention it will be obvious to those skilled in the art, that various changes and modifications may be made therein without departing from the inventive concept contained therein and it is, therefore, aimed to cover all such changes and modifications as fall within the true spirit and scope of the invention.

We claim as our invention:

1. Mass spectrometer apparatus comprising, in combination:

mass analyzer means including a front panel provided with an entrance aperture and defining a longitudinal ion input path passing through said aperture and extending transverse to said front panel;

means for supporting a target electrode arranged to carry a sample to be tested for permitting the sample to be struck by a primary ion beam at a point laterally offset from said ion input path for producing particles by sputtering;

shutter means presenting a beam-defining aperture for the passage of a beam of such particles from said sample, said beam defining aperture being positioned such that the straight line between the point at which the primary ion beam strikes the sample and the center of said beam-defining aperture intersects said front panel at a point outside the region enclosed by said entrance aperture and intersects the line defining said longitudinal ion input path at a point between said front panel and said shutter means; and

means for producing an electric field in the region between said shutter means and said front panel to deflect the low energy ions in said beam of particles through said entrance aperture and along said ion input path, said electric field producing means including a pair of electrodes disposed between said front panel and said shutter means and located to respectively opposite sides of the line defining said longitudinal input path, said electrodes being spaced from the straight-line path between the center of said beam-defining aperture and the point where said front panel is intersected by said straight line between the point where the primary ion beam strikes the sample and the center of said

beam-defining aperture, whereby neutral particles and high energy ions passing through said beam-defining aperture strike said front panel outside the region enclosed by said entrance aperture and are thus prevented from entering said mass analyzer means.

2. An arrangement as defined in claim 1 wherein said pair of electrodes constitute plate electrodes of a plate capacitor.

3. An arrangement as defined in claim 1 further comprising mounting means supporting at least one of the following: said shutter means and said target electrode supporting means, for movement in a direction transverse to said longitudinal ion input path for varying the angle between said longitudinal ion path and the straight line between the center of said beam-defining aperture and the point at which the primary ion beam strikes the sample.

4. An arrangement as defined in claim 1 wherein at least one of the following: said sample, said target electrode, and said shutter means is arranged to be placed at an electrostatic potential relative to the potential of said mass analyzer for optimizing the line intensity in the mass spectra produced at the output of said mass analyzer.

5. An arrangement as defined in claim 1 wherein said mass analyzer means is a quadrupole mass analyzer.

6. The device of claim 1 wherein the electric field is a static one.
